UNITED STATES PATENT OFFICE.

AUGUST TEGOLI, OF SANTA ROSA, CALIFORNIA, ASSIGNOR OF ONE-HALF TO CHARLES BERTOLI, OF SANTA ROSA, CALIFORNIA.

DRYING APPARATUS.

1,165,917.

Specification of Letters Patent. Patented Dec. 28, 1915.

Application filed June 11, 1915. Serial No. 33,543.

To all whom it may concern:

Be it known that I, AUGUST TEGOLI, a subject of Italy, residing at Santa Rosa, in the county of Sonoma and State of California, have invented certain new and useful Improvements in Drying Apparatus, of which the following is a specification, reference being had to the accompanying drawings.

- 10 This invention relates to certain improvements in drying apparatus and has relation more particularly to an apparatus of this general character especially designed and adapted for use in drying pastes, such as 15 vermicelli or the like; and it is an object of my invention to provide an apparatus of this general character having novel and improved means whereby the time for drying the paste may be materially decreased.
- 20 It is also an object of my invention to provide a novel and improved apparatus of this general character whereby the paste may be dried in such a manner as to prevent souring or molding and to avoid curling, cracking, or breaking whereby a superior product is assured.

30 The invention consists in the details of construction and in the combination and arrangement of the several parts of my improved drying apparatus whereby certain important advantages are attained and the device is rendered simpler, less expensive and otherwise more convenient and advantageous for use, all as will be hereinafter 35 more fully set forth.

The novel features of the invention will be carefully defined in the appended claims.

In order that my invention may be the better understood, I will now proceed to describe the same with reference to the accompanying drawings, wherein—

40 Figure 1 is a view, partly in top plan and partly in section, of a drying apparatus constructed in accordance with an embodiment of my invention; Fig. 2 is a fragmentary vertical section, on an enlarged scale, taken through the apparatus as herein disclosed; and Fig. 3 is a fragmentary view, partly in elevation and partly in section, 45 illustrating the means herein disclosed for tilting the supporting frames.

50 As disclosed in the accompanying drawings, 1 denotes a drying chamber of predetermined configuration and dimensions having its opposite ends open and adapted

to be closed, preferably, by the sliding doors 2—2, as is thought to be clearly shown in the accompanying drawings. The chamber 1 is divided into two compartments *a* and *b* through the medium of the interposed partition 3 having a central opening 4 in which is rotatably mounted the fan 5, the blades whereof project into both of the compartments *a* and *b*.

55 The fan 5 includes the horizontally disposed supporting axle 6 adapted to be operatively engaged in any desired manner with a suitable source of power, and it is to be understood that said shaft may be reversely rotated in accordance with the necessities of practice. Each of the compartments *a* and *b* and preferably adjacent the partition 3 is provided with an entrance opening 7 closed by the conventional doors 8, said openings affording a convenient means whereby desired attention may be given to the fan.

60 Each of the compartments *a* and *b* has disposed thereacross the vertically aligned spaced shafts 10 mounted for rocking movement and one of said shafts, preferably 65 an intermediate shaft, has its extremities extending exteriorly of the chamber, and to each of said projected extremities is secured an operating lever 11, for a purpose to be hereinafter more particularly referred to.

70 Secured to each of the shafts 10 adjacent the extremities thereof are the rock bars 12 extending beyond opposite sides of the shaft and having their extremities pivotally engaged with the vertically disposed bars 14. The bars 14 are connected by the frame 15 disposed in the same general direction as the bars 12 and pivotally engaged with said bars 14 whereby it will be perceived that 75 upon rocking movement being effected through the medium of the operating lever 11, the angle of adjustment of the frames may be varied so that the current generated by the fan 5 may be drawn or pressed either 80 upwardly through the frames or downwardly therethrough. The frames 15 are adapted to have positioned thereon the trays 16 formed preferably of a wire mesh and in which the paste to be dried is placed, said 85 paste being preferably coiled within the trays. It will be readily observed that the open ends of the chamber 1 afford a medium whereby the trays may be readily applied to or removed from the frames.

From the foregoing description, it is thought to be obvious that a drying apparatus constructed in accordance with my invention is of an extremely simple and 5 comparatively inexpensive nature, and is particularly well adapted for use by reason of the convenience and facility with which it may be assembled, and it will also be obvious that my invention is susceptible of 10 some change and modification without material departure from the principles and spirit thereof and for this reason I do not wish to be understood as limiting myself to the precise arrangement and formation of 15 the several parts herein shown in carrying out my invention in practice.

I claim:

1. A drying apparatus comprising a chamber, frames mounted for rocking movement within the chamber, means exterior of the chamber for imparting rocking movement to the frames, and means for causing a circulation of air to coact with the frames.

2. A drying apparatus comprising a chamber, frames mounted for rocking movement within the chamber, means for imparting rocking movement to the frames, means for causing a circulation of air to coact with the frames, the opposite ends of the chamber being open, and closure members therefor.

3. A drying apparatus comprising a chamber divided into two compartments, means common to both of said compartments for creating air circulation therein, supporting frames within each of the compartments mounted for rocking movement, each of said compartments being provided with an entrance opening, and a closure member for each of said openings.

In testimony whereof I hereunto affix my signature in the presence of two witnesses.

AUGUST TEGOLI.
